Primary Examiner—Cathron Brooks*Assistant Examiner*—Deanna Fluegeman(74) *Attorney, Agent, or Firm*—Wei Te Chung(57) **CLAIM**

The ornamental design for a memory card reader, as shown and described.

DESCRIPTION

FIG. 1 is a perspective view of a memory card reader showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a schematic view of using the memory card reader.

The broken line showing of portions of the memory card reader are included for illustrative purposes only and form no part of the claimed design.
